BINDER-STRAPPING REEL

Loman O. Green, Chicago, Ill., assignor to Sigma
node Steel Strapping Company, Chicago, Ill., a
corporation of Delaware

Application May 4, 1949, Serial No. 91,403

4 Claims. (Cl. 242—105)

1

My invention relates to binder-strapping reels. It will be illustrated and explained as embodied in a reel particularly adapted for steel binder-strapping of the flat or ribbon variety.

In the binding of packages or bundles and other uses binder strapping is in the great majority of cases taken from coils. The removal of strapping from coils as desired has always presented a problem. Reels rotatably to hold the coils have been devised but simply supporting a coil for rotation does not overcome the difficulties. When strap is pulled from a coil on a reel, the momentum of the reel and its coil, especially that built up by the initial force required to start the reel turning from a condition of rest, tends to produce overrunning; that is, the reel and coil continue to rotate after the paying out of the strapping ceases because the operator is no longer pulling upon it or not taking it as fast as it is uncoiled. The result is not so-called "backlash" such as experienced with casting reels where the greater speed of the spool actually causes line to be rewound in reverse direction; the inherent stiffness of even highly flexible steel binder strapping prevents any such reverse winding. However, looseness among the outer convolutions or turns of a strap coil on a free running reel does occur when strap is pulled from the coil. This looseness, coupled with the strap stiffness causes convolutions of strapping remaining on the coil to become crossed, inverted in relative position and, for want of a better term, otherwise generally "scrambled." Not infrequently looseness may be such that outer coil convolutions will expand and enlarge beyond the diameter of the reel-drum heads, requiring that they be carefully centered, when strap is again removed, to prevent them from shrinking outside of the reel and interfering with its rotation. The result is that the strap can be removed only with difficulty if at all and much time and effort may be consumed in re-arranging coil convolutions at more or less frequent intervals in order to be able to feed any strap at all from the reel.

A wide variety of reel brakes have been proposed and used to prevent such strap reels from overrunning with the result mentioned; but whereas a proper brake may prevent overrunning, it injects other objectionable characteristics. Thus when strap removal is done manually—as is probably most frequently the case—a brake which is active whenever strap is being pulled from the reel creates a drag opposing the operator's pull and against which the operator must always work. The effect may become very tiring.

2

Some varieties of brakes apply braking effects more or less continuously whenever and as long as the reel rotates with the result that, not only must the operator work against the drag of the brake when pulling strap from the reel as just mentioned, but as soon as pull ceases, feeding of the strap also substantially ceases. This characteristic of continuously applied brakes presents a second disadvantage under many frequently encountered service conditions. With such a brake an operator can conveniently remove from the reel only a limited amount of strap at each pull. The amount which can be removed will vary depending upon the force exerted by the operator, the adjustment of the brake, and other factors; but around five or six feet per pull may be taken as a fair average. This length of strap is insufficient for many purposes. For example, only relatively small bundles or packages can be encircled or looped by this length of strap. Consequently when larger objects are to be bound or for other reasons the operator finds it convenient to remove a greater length of strap preparatory to looping operations, it becomes necessary for him to pull strap from the reel more than once before or in the course of looping. This is not only tiring but also time consuming. Furthermore, in many binding operations, even upon small packages, such as in what may be termed "chain" or "team" work, operators find it quicker, less fatiguing and more convenient to take from a reel enough strap during each removal to perform several binding operations before repeating the removal operation. Not infrequently conditions are such that the most convenient technique for quickly binding large numbers of bundles or packages is for an operator to remove from a reel many feet of strapping, which may be laid along the floor or bench, preparatory to the actual looping of the binder about the packages or bundles. With a continuously acting brake these methods can be used only by removing the desired amount of strap from the reel by the requisite number of pulls between looping operations, each pull resulting in the paying out of only a relatively short length of binder. Other brakes have been arranged automatically to release when strap is being pulled and to become effective when pull ceases. Such an arrangement, while lessening or overcoming the objectionable drag throughout a pulling operation requires some extra effort to release the brake, as well as that always required to start the reel rotating. And it does not overcome the objec-

tions due to the limitation in the amount of strap that can be removed by a single pull.

The principal object of my invention is to provide a reel for flexible metallic binder strapping which will materially lessen, if not entirely eliminate, overrunning; which will not inject a drag upon the operator when strap is being removed; and which will permit more strap to be removed by a single pull than is the case when reel brakes are employed.

Another object is to provide a reel which, although possessing the above mentioned desirable characteristics, is simple, inexpensive, and reliable.

Other objects and advantages will hereinafter appear.

In the accompanying drawings, which illustrate the preferred embodiment of my invention:

Fig. 1 is a front elevation of the reel;

Fig. 2 is a side elevation;

Fig. 3 is a slightly enlarged section on the line 3—3 of Fig. 1; and

Fig. 4 is a greatly enlarged section on the line 4—4 of Fig. 2.

The complete reel includes a wheeled tubular stand or cart A, a two-section strap-coil holding drum B and a strap-delivery control C.

The reel stand A has a base 10 of substantially U shape in plan, the side members 11 and 12 of which are bent downwardly at the front and joined by the yoke 13 as shown clearly in Figs. 1, 2 and 3. Yoke 13 forms a foot for facilitating the retention of the stand in an upright position, which is the position normally assumed in use. It also has a coil-drum supporting handle 14 of substantially U-shape in elevation, the side members 15 and 16 of which are bent rearwardly at their upper ends and joined by a yoke 17 as shown most clearly in Fig. 1. Yoke 17 forms a convenient grip for the operator in moving the stand from place to place and also as a supporting leg when the stand is tipped down for convenient loading with a coil. The base 10 and handle 14 may be made of single pieces of iron tubing, the ends of the side members of the handle being joined at substantially right angles to the side members of the base in any desired and suitable manner, such as the brazed joints 18 indicated in Fig. 3. The frame or stand may be made more rigid and stronger by a brace 19 secured at its upper end to a rod 20 bridging between the side members 15 and 16 of the handle and secured at its lower end to a rod 21 bridging between the side members 11 and 12 of the stand base. If desired, rod 21 may be extended beyond the base frame members 11 and 12 to accommodate a pair of wheels 22 and 23. Such wheels not only facilitate movement of the stand and its load but, together with the yoke 13, constitute the stand's supporting feet when it stands upright.

The strap-coil holding drum B comprises two separable complementary sections, which when assembled form a cylindrical hub 25 for accommodating the central opening of a coil of metallic binder strapping, flanked by two spaced parallel cylindrical drum heads 26 and 27 which among other functions to be later explained, serve to retain a strap-coil in place on the drum hub. The two complementary drum sections 30 and 31 are made of sheet steel or other suitable material in generally disc-like form having the parallel outer flanges 28 and 29 which form the opposite drum heads and annular intermediate shoulders which, when the sections are together, form the coil supporting drum hub 25 as shown most

clearly in Fig. 3. Section 30 is permanently but rotatably mounted on the frame or stand by means of a hub 32 journaled on a stud shaft 33. Shaft 33 has its rear end suitably anchored as by welds 34 to a yoke 35 which bridges between and is rigidly secured, as by welding, to the handle side members 15 and 16. If desired, yoke 35 may be extended at each end and, beyond the peripheries of the drum, bent forwardly to provide guards 36 and 37, which serve to shield the drum against contact with other objects. Hub 32 has a rear annular flange 38 to which the inner edge about a central opening of rear drum section 30 is secured by rivets 39. Near its forward or outer end, hub 32 is provided with a flange 40 which forms an abutment for a clamp ring 41 secured by rivets 42 to the inner edge about a central opening through front drum section 31. The outer or forward end of hub 32 is threaded to receive a wing nut 43.

The rear drum section 30 always remains on the stand but by removing wing nut 43 the forward drum section 31 may be removed for ready application of a strap-coil. When a coil is positioned on the half-hub of rear section 30, the forward section 31 may be replaced and secured by wing nut 43 whereupon the coil is carried by the whole hub and retained in place by the two heads.

The strap-feed or delivery control C comprises in general a strap feeding roller 50, which is in alignment with the drum hub and rotated by a pair of driving rollers 51 and 52 in alignment and contact with the peripheries of drum heads 26 and 27 and rotated thereby when the drum turns, and a pressure roller 53 in alignment with feeding roller 50. Strap delivered from the drum is passed between the driven and pressure rollers, the latter holding the strap against the peripheral surface of the feeding roller. The strap feeding, the two driving and the pressure rollers are carried by a generally U-shaped bracket having side plates 55 and 56 which are journaled on a post 57 projecting from and rigidly secured to side member 15 of the stand handle 14. Side plates 55 and 56 journal a shaft 60. Between side plates 55 and 56 shaft 60 carries the feeding roller 50 and outside of the side plates this shaft 60 carries the two driving rollers 51 and 52. Preferably all three of these rollers are formed of resilient material, such as a rather stiff rubber or rubber composition, so that the driving rollers will have good traction with the drum rims and the feeding roller will have good traction with the strap and be sufficiently compressible to accommodate itself to variations in strap thickness as the pressure roller presses the strap thereagainst. The strap feeding and driving rollers may be securely fastened to shaft 60 so as to be rotatable together in various ways, such as by providing the shaft with knurled portions 62 upon which the rollers may be pressed, as indicated in Fig. 4.

The bracket is biased to cause the driving rollers 51 and 52 to contact the peripheries of drum heads 26 and 27, respectively. This biasing is accomplished by a coil spring 65 which surrounds post 57 and has one end 66 engaging side member 15 of the handle and its other end 67 engaging the side plate 55 of the bracket.

In operation the strap feeding roller is driven by the engagement of its two driving rollers upon the peripheries of the drum heads. When strap is pulled from the reel and the drum starts to rotate, the strap feeding wheel, being driven by the drum heads, which are always of greater

diameter than the strap coil, and through a high ratio between the diameter of the drum head peripheries and the diameter of the driving rollers, tends to withdraw strap from the reel drum at a faster rate than strap is unwound from the drum by the drum's rotation. The result is that the strap is payed out as fast as it unwinds from the drum so that there is no objectionable slack in the strap on the drum and there is no appreciable drag either upon the drum or upon the strap being withdrawn from the drum. Frequently steel binder strapping is lubricated to facilitate its slippage around bundle corners during tensioning operation and its passage through some varieties of binder tensioning tools. Such lubricated strapping is fed from my improved reel without objectional slack and overrunning as readily as is unlubricated or so-called "dry" strapping.

If desired a metallic bin 70 for holding binder-joint seals and a shelf 71 for holding binder tools may be located between and attached to the upper ends of the side members 15 and 16 of the handle, as indicated in Figs. 1 and 2.

Having thus illustrated and explained the nature and a preferred embodiment of my invention, what I claim and desire to secure by United States Letters Patent is as follows:

1. A reel for metallic binder-strapping comprising a frame, a strap-coil holding drum rotatably mounted on the frame, the drum having a coil carrying hub and a cylindrical coil retaining head, a bracket pivotally mounted on the frame, a shaft journaled in the bracket, the shaft carrying and having fixed thereto a strap feeding roller and a driving roller, the feeding roller aligning with the drum hub and the driving roller aligning with the drum head, a pressure roller carried by the bracket in alignment with the strap feeding roller, the spacing between the peripheries of the strap feeding and pressure rollers being such as to enable rotation of the strap feeding roller to feed strap therebetween, and a spring for biasing the bracket to cause the driving roller to engage the drum head so as to be rotated thereby.

2. A reel for metallic binder-strapping comprising a frame, a strap-coil holding drum rotatably mounted on the frame, the drum having a coil carrying hub flanked by a pair of cylindrical coil retaining heads, a bracket pivotally mounted on the frame, a shaft journaled in the bracket, the shaft carrying and having fixed thereto a strap feeding roller aligning with the drum hub and a driving roller at each side of the feeding roller aligning with one of the drum heads to engage and be rotated thereby, a spring biasing the bracket to press the feeding rollers against

the rims of the drum heads, and a pressure roller carried by the frame, the spacing between the peripheries of the feeding and pressure rollers being such as to enable rotation of the feeding roller by the drum to feed strap between the feeding and pressure rollers.

3. A reel for metallic binder-strapping comprising a frame, a strap-coil holding drum rotatably mounted on the frame, the drum having a coil carrying hub flanked by a pair of cylindrical coil retaining heads, a bracket pivotally mounted on the frame, a shaft journaled in the bracket, the shaft carrying and having fixed thereto a resilient strap feeding roller aligning with the drum hub and a driving roller at each side of the feeding roller aligning with one of the drum heads to engage and be rotated thereby, a spring biasing the bracket to press the feeding rollers against the rims of the drum heads, and a pressure roller carried by the frame, the spacing between the peripheries of the feeding and pressure rollers being such as to enable rotation of the feeding roller by the drum to feed strap between the feeding and pressure rollers.
4. A reel for metallic binder-strapping comprising a frame, a strap-coil holding drum rotatably mounted on the frame, the drum having a coil carrying hub flanked by a pair of cylindrical coil retaining heads, a bracket pivotally mounted on the frame, a shaft journaled in the bracket, the shaft carrying and having fixed thereto a rubberlike strap feeding roller aligning with the drum hub and a driving roller at each side of the feeding roller aligning with one of the drum heads to engage and be rotated thereby, a spring biasing the bracket to press the feeding rollers against the rims of the drum heads, and a pressure roller carried by the frame, the spacing between the peripheries of the feeding and pressure rollers being such as to enable rotation of the feeding roller by the drum to feed strap between the feeding and pressure rollers.
